UNITED STATES PATENT OFFICE

2,574,118

RAILROAD TRACK CRIB CLEANING APPARATUS

James B. McWilliams, Pittsburgh, Pa., assignor to Railway Maintenance Corporation, Pittsburgh, Pa., a corporation of Pennsylvania

Application January 20, 1948, Serial No. 3,284

2 Claims. (Cl. 37—104)

1

This application relates to apparatus which will clean railroad track ballast. It is particularly designed for cleaning ballast in the cribs of railroad tracks; i. e., in the spaces between the ties.

My apparatus removes all of the material from the cribs, including ballast and cinders, dirt, mud, etc., which have accumulated in the ballast. It is highly desirable to remove the dirt, cinders, etc., from the ballast inasmuch as they prevent proper drainage of the roadbed, but this is a difficult operation to perform by machinery because not only is the space between the ties rather narrow but the track rails make access to the space rather difficult. My apparatus, however, removes all the material from the crib, separates the undesired material such as the dirt and cinders from the ballast, returns the ballast to the cribs and conveys the dirt, cinders, etc. to a position where they may be disposed of.

The apparatus described and claimed in this application is an improvement on apparatus which is disclosed in my prior Patents Nos. 2,132,176 and 2,358,657 as will hereinafter appear.

Generally speaking, a machine constructed in accordance with my invention comprises a car having flanged wheels so that it can run on the railroad tracks which are to be cleaned. The car carries material moving means or pusher arms which move in the crib outside and under the rails towards the center of the crib so as to force material in the end portions of the crib towards its center. The car also has digging conveyors which remove material which has been pushed into the central portion by the pusher arms and which excavate the central portion. The conveyors and rams are supported by a carriage which is movable vertically on the car so that the equipment can be moved from one crib to the next. The depth to which material is moved from the cribs can also be regulated.

Material in the buckets flows on to chutes which deliver it to a shaker screen which separates the ballast from the dirt, cinders, etc. The screen is vibrated so as to move the ballast onto an apron from which it is delivered by chutes back to the cribs. A hopper beneath the screen catches the screenings. They are carried from the hopper by a screw conveyor to a belt conveyor which carries them to a suitable position for disposal.

In the accompanying drawings I have illustrated a present preferred embodiment of my invention in which

Figure 1 is a side elevation of my apparatus; Figure 2 is a plan elevation;

2

Figure 3 is a section on the lines III—III of Figure 2 with the tie in front of the crib which is being cleaned removed.

Figure 4 is a horizontal section along the lines IV—IV of Figure 3.

Figure 5 is a section along the lines V—V of Figure 1 with certain portions removed for purposes of illustration;

Figure 6 is a vertical section through the lower end of the bucket conveyor and digging mechanism, the plane of the section being indicated by the lines VI—VI in Figure 2;

Figure 7 is a horizontal section along the lines VII—VII of Figure 5;

Figure 8 is a fragmentary end view (viewing my apparatus from the plane indicated by the arrows VIII—VIII in Figure 6);

Figure 9 is a fragmentary end view (viewing my apparatus from the plane indicated by the arrows IX—IX in Figure 6);

Figure 10 is a diagrammatic showing of the power system used for driving the various operating parts of my apparatus;

Figure 11 is a fragmentary vertical section along the lines XI—XI of Figure 5;

Figure 12 is a fragmentary plan view showing a belt conveyor used in my apparatus; and

Figure 13 is an end elevation of the structure shown in Figure 12.

Ballast cleaning apparatus constructed in accordance with my invention comprises a car 13 mounted on flanged wheels 14 so that the car can run on rails 15 of a railroad track. The rails are supported by ties 16 in the conventional manner which form cribs holding the ballast to be cleaned by my apparatus.

The car carries a framework 17 which supports or on which are mounted the various operative parts of my apparatus. A carriage designated generally by the reference number 18 is carried by the car adjacent one end. This carriage supports digging conveyors 19 and 20 comprising buckets carried on endless chains as well as pusher arms 21 which force material from the ends of the cribs towards their centers into the path of the digging conveyors. The construction and operation of the digging conveyors and pusher arms will be described more in detail hereinafter.

The other end of the car 13 carries a power unit for driving the various operating parts of my apparatus. The power equipment includes a gas or diesel engine 13a which drives a hydraulic pump 13b which supplies fluid under pressure to fluid motors and to various cylinders. The system whereby fluid is supplied under pres-

sure to the various parts of my apparatus and the manner in which this supply is controlled will be hereinafter described. The engine 13a also drives some operating parts through direct mechanical connections.

The carriage 18 may be moved vertically to lift the bucket conveyors and the pusher arms up out of a crib and down into another crib. The carriage 18 carries two pairs of collars 22 which are secured around two columns 23 and 24 mounted on the car 13 and make a sliding fit therewith. A piston 25 operating in a cylinder 26 and positioned under a bracket 27b secured to a back cross-beam 27' on the carriage raises the entire carriage when fluid under pressure is supplied to the cylinder 26 through the pipe 26a. The columns 23 and 24 guide the vertical movement of the carriage 18. They in turn are braced by the framework 17 as is shown in Figure 1.

The digging conveyors 19 and 20 discharge the material from the cribs onto chutes 31 from which it flows onto a screen 32. This screen is inclined and is also vibrated as will be herein-after described. By reason thereof, the ballast passes from the screen 32 onto an apron 33 forming part of the screen and is then directed by baffles 34 onto chutes 35 which distribute it to opposite ends of the cribs. Some of the ballast passes between the baffles and falls off the edge of the apron 33 into the central portion of the cribs. Dirt, cinders, and other screenings from the screen 32 fall through the screen into a hopper 36 which feeds the material into the lower end of a screw conveyor 37. The screw conveyor deposits the material onto a belt conveyor 38 which carries the material to a suitable position for disposal.

The carriage 18, the digging conveyors 19 and 20 and the pusher arms 21 are illustrated in detail in Figures 3 to 9, inclusive. The carriage comprises a framework having vertical channels 39 connected by front and back plates 40 and 41 and cross-beams 27 and 27', 42 and 42' and a top crossframe 43. Two digging conveyors are carried by the frame 18. Top sprocket wheels 44 for the chains of the conveyors rotate on axles 45 journaled on the top crossframe 43. Bottom sprockets 46 are journaled in blocks 47 which slide in vertical guides 48 welded to front and rear crossplates 40 and 41.

Means are provided for taking up slack in the chains which is caused by wear. The means are shown in Figure 6 and comprise bolts 49 threaded into brackets 50 welded to the plates 40 and 41. Turning the bolts 49 in the brackets 50 brings them against brackets 50a on the blocks 47 and forces the blocks 47 downwardly so as to tighten the chains. A lock nut 51 holds the bolts 49 in a desired position.

As shown in Figure 3, the two digging conveyors rotate about their sprockets in opposite directions and the buckets are mounted on the conveyors in such manner that the buckets of one conveyor open into or feed the buckets of the other conveyor. Material in the track crib which is moved by a bucket of one conveyor but not picked up by that conveyor is moved into the path of the bucket in the other conveyor. The conveyors are driven by the gas or diesel engine 13a by means of chain drives 52 and 53, the chain drive 53 leading to a driveshaft 54 which is connected by a universal joint 55 to the shaft 56 on which the upper sprocket of the chain drive 53 is mounted. The driveshaft 54 is connected through a universal joint 57 to a shaft 58

journaled in the top frame 43. A pinion gear 59 secured to the shaft 58 meshes with a gear 60 mounted on the same shaft as the sprocket 44 for the conveyor 20. The gear 60 meshes with a gear 61 mounted on the same shaft as the sprocket 44 for the conveyor 19. An overload clutch 62 is provided between the shaft 56 and the upper sprocket of the chain drive 53 to prevent damage to the drive and the conveyors in the event they should jam in a track crib.

As before noted, the carriage 18 is movable vertically on the columns 23 and 24. To limit the depth to which the conveyors will move the material from the central portion of a crib the side channels 39 of the carriage carry adjustable stops 63 (Figure 3) which, when the carriage is lowered, abut against the track rails and thus limit downward movement of the carriage. The construction of the stops is shown more in detail in Figures 6, 7 and 8. Each stop 63 comprises a flat plate 64 which is held to the channel 39 by bolts 65, which pass through a slot 66 in the plate so that the plate may be raised or lowered relative to the channel 39. The plate 64 carries two outwardly extending ribs 67, the lower portions of which increase in width and thickness at 68. A notch 69 is cut in the bottom of the edge rib 67, the width of this notch being sufficient to engage the opposite top edges of the head of a track rail as shown in Figure 6. A second plate 70 is bolted to the channel 39 above the plate 64, to hold the latter plate in the desired vertical position. The plate 70 has a series of holes 71 through which a stud 72 may be passed. The vertical position of the plate 70 and consequently of the plate 64 may thus be adjusted in relation to the carriage 18. Since the ribs 67 of the plate 64 engage the track rails, the depth to which the digging conveyors and the pusher arms remove material from the track cribs can be determined by selecting one of the several holes 71 in the plate 70.

My apparatus has two pusher arms 21 which are employed to move ballast from the ends of a crib towards its center and into the path of the digging conveyors. Each pusher arm is formed from a plate 73 having a peripheral flange 74 for strength and rigidity. The pusher arm at its upper end rotates about a pin 75 carried by the cross-beams 42 and 42'. The lower end of the plate 73 carries an inwardly turned arm 73a on which is mounted a head 76 which as shown in Figure 9 will pass between adjacent ties and under the track rail. Each arm also carries a paddle or a flapper 77 which is hinged at one end just to the rear of the head 76. On the inward stroke of the pusher arm the paddle 77 rides on top of the ballast. On the outward stroke of the pusher arm, however, the paddle rotates until it abuts against the rear of the head 76 whereupon it will remove ballast from the extreme outer ends of a crib. The path of the free end of the paddle 77 is shown in chain lines in Figure 3.

As shown in detail in Figures 6 and 9, the length of the pusher arms 21 may be adjusted. The bottom inwardly turned arm 73a of the pusher arm is made separate from the plate 73 and secured to the plate by bolts 78. The plate has bolt slots 79 so that the arm can be raised and lowered relative to the plate and held in the desired position by tightening the bolts 78.

As shown in Figures 3 and 5, each pusher arm is rotated about a pin 75 by a piston 80 operating in a cylinder 81. Each piston 80 is hinged to an ear 82 on each pusher arm and the opposite end 75 of the cylinder 81 rotates about a pin 83 which

is carried by the cross beams 27 and 27'. As shown in Figure 5, fluid under pressure is supplied to either end of each cylinder 81 through the pipe 84 and flexible hose 84' to rotate the pusher arms towards the center of the crib and through the pipe 85 and flexible hose 85' to withdraw the pusher arms.

As shown in Figure 3, the carriage 18 also carries drop plates 86 which rest on the two ties forming the crib from which ballast is being removed (see also Figures 8, 9 and 11). The plates extend substantially from rail to rail and serve to prevent material which is being pushed by the pusher arms or lifted by the bucket conveyors from spilling onto the tops of the ties. Bolts 87 which secure the plates to the carriage pass through slots 88 in the plates so that within limits the plates will rest on the top of the ties irrespective of the depth to which ballast is removed from the crib. The bottom edge of each plate carries runners 89 which prevent the plates from dropping down between the ties in the event the ties are unevenly spaced.

Arms 90 bolted to each side of the carriage as at 91 carry U-shaped plates 92. The legs of each plate rest outside the rails on the top surface of two adjacent ties which form the crib to be cleaned, the pusher arms passing between the legs (see Figure 7). The plates 92 thus perform the same function outside the rails as the plates 86 between the rails and also prevent material from piling up on to the rail base. Each arm 90 has a slot 93 which performs the same function as the slots 88 in the plates 86.

As above noted, the digging conveyors 19 and 20 empty into chutes 31 which deliver the material to a screen 32. This screen is mounted for reciprocating motion on rocker arms 94 and is rocked by an eccentric 95. The chain drive 52 drives a shaft 96 through a clutch 97. The shaft 96 turns a right angle drive 98 which in turn actuates the eccentric 95 by means of a chain drive 99.

As above noted, ballast passes from the screen onto an apron 33 where it is directed by the baffles 34 onto the chutes 35 or over the end of the apron into the cribs. Screenings pass into a hopper 36 which leads to a screw conveyor 37. This conveyor is driven by a chain drive 100 which in turn is driven by the right angle drive 98. The screw conveyor carries the screenings onto a belt conveyor 38 of conventional form through a chute 39.

A bracket 101 extending down from the rear end of the car 13 carries the receiving end of the conveyor 38. Side plates 102 of the conveyor are journaled at the receiving end of the conveyor in a yoke 103, the yoke 103 rotating about a pin 104 carried by the bracket 101. The discharge end of the conveyor can, therefore, be raised or lowered and the entire conveyor can be swung in a horizontal plane about the end of the car. Stays 105 secured to the top of the frame 11 support the conveyor.

To hold the conveyor 38 at the desired angle to the track being cleaned a lever 106 fits into notches 107 cut in the edge of the bracket 101, the lever 106 being resiliently held in the notches by a spring 108. A hand lever 109 at the end of the conveyor is connected to the lever 106 by a rod 110 and can be used to withdraw the lever 106 from the notches in the bracket 101 in order to swing the conveyor to a different position. A fluid motor 111 carried on the conveyor drives the belt 112 of the conveyor through the chain drive 70

113. This hydraulic drive permits the conveyor to be rotated in a horizontal plane without the use of complicated gearing which would otherwise be necessary if a direct drive from the Diesel or gas engine 13a to the belt conveyor were used.

The car is moved from one crib to another by a fluid motor 114 which drives a transmission 115 through the chain drive 116. The transmission is connected to the rear axle of the car by a chain drive 117. A chain drive 118 connects the front axle with the rear axle so as to obtain a four-wheel drive.

Figure 10 shows diagrammatically the circuit whereby fluid under pressure is supplied to the various operating parts which are actuated by fluid motors or hydraulic cylinders and the manner in which the supply is controlled. The engine 13a drives a hydraulic pump 13b which supplies fluid under pressure through a closed system formed by outgoing pipes 119 and return pipes 120 and including a tank 121.

The motor 111 which drives the belt conveyor 38 runs continuously. It is therefore permanently connected into the line 119, the amount of fluid supplied to the motor being controlled by a valve 122.

Valves 123, 124 and 125 operated by levers 123', 124' and 125' control the flow of fluid to the cylinder 26 which raises the carriage 18, to the motor 114 which drives the car wheels, and to the cylinders 81 which actuate the pusher arms 21, respectively. Valves 123, 124 and 125 are all open center valves and permit a continuous flow of fluid through the pipes 119 and 120 until they are turned to admit fluid to the device whose operation they control. When the valve 123 is actuated to lift the carriage 18, the fluid flows through pipes 126, 127, through a check valve 128 and thence to the cylinder 26 through a pipe 129. Fluid also flows through a variable valve 130 to the cylinder 26. The carriage is lowered by reversing the valve 123, the rate of descent being controlled by the valve 130.

When the carriage descends, the check valve 128 is, of course, closed, the purpose of this valve being to provide an extra passageway for the flow of fluid into the cylinder 26 to raise the carriage more rapidly than if fluid flowed only through the valve 130. The operation of the four-way valve 124 which controls the motor 114 which drives the car wheels is conventional. The motor is reversible, the direction of rotation being determined by the direction in which the valve directs fluid to the motor.

As shown in Figure 10, the supply of hydraulic fluid under pressure to both of the cylinders 81 which actuate the pusher arms 21 is controlled by one valve 125, a feature which has been found to be of considerable value in practice. If one pusher arm should be jammed against some obstruction in a crib such as an unusually large stone, all of the pressure will be directed to the cylinder which actuates the other pusher arm so that it will complete its stroke. All of the pressure will then be directed to the cylinder which actuates the jammed pusher arm and the additional pressure has been found in most cases to be sufficient to free the pusher arm.

The normal operation of my apparatus will now be described. The machine is placed on a track so that the digging conveyors and pusher arms are in line with a track crib. The depth to which it is desired to remove material from the crib is determined and the stops 63 are adjusted accordingly. The clutch 97 is thrown in

to start the digging conveyors, the screw conveyors 37, and the eccentric 95 which rocks the screen 32. The carriage 18 is then lowered. As the carriage drops the digging conveyors excavate the central portion of the crib until the stops 63 strike the heads of the rails 15. The pusher arms 21 are then moved inwardly between ends of the crib from the position shown in chain lines in Figure 3 until the final position shown in solid lines in the same figure to push material from the ends of the crib into the path of the conveyors. Then the pusher arms 21 are swung outwardly. When the pusher arms have reached their extreme outward position the carriage 18 is lifted and fluid is supplied to the motor 114 to move the car forward until the conveyors and pusher arms are over the next crib. This process is repeated for the length of the track to be cleaned.

From the foregoing it will be appreciated that my apparatus provides a wholly mechanical method for cleaning ballast in railroad track cribs. It operates more rapidly and more satisfactorily than any machine intended for the same purpose with which I am familiar. It is carried entirely on the track which is being cleaned. The pusher arms are relatively short in length so that when they are in the open position they do not project across and block adjacent tracks. In spite of the relatively short stroke the full length of the crib is cleaned because of the paddles 77. The guard plates 86 and 92 keep material off the tie tops so that all material is removed from the cribs.

Other features worthy of note are (1) the two digging conveyors 19 and 20 which are mounted and rotated so that the buckets on the conveyors feed into each other. Material loosened but not picked up by a bucket on one conveyor is nevertheless moved by that bucket into the path of the bucket on the other conveyor; and (2) the control of both pusher arms through a single valve, the advantages of which have been described above.

Relative vertical adjustment of the various digging elements is provided. First the depth to

which the conveyors excavate the central portion of the crib is determined by the stops 63. Play in the chains of the digging conveyors which is created by wear can be taken up as it develops. This adjustment will increase the depth to which the bucket conveyors will excavate in the crib. However, the stops 63 can be reset to take care of this fact. The length of the pusher arms 21 can be varied so that the pusher arms can remove material from the ends of the cribs to the same depth as the material is removed from the center of the cribs or, within limits, to any depth desired.

While I have described a present preferred embodiment of my invention, it is to be understood that it may be otherwise embodied within the scope of the following claims.

I claim:

1. Apparatus for cleaning ballast in railroad track cribs comprising a support, means carried by the support for removing material from the crib, plates slidably mounted on the support for vertical movement, said plates extending vertically from the tops of the ties forming the cribs and substantially the full distance between the rails, said plates serving to prevent material being moved from the crib from spilling onto the ties.

2. Apparatus as described in claim 1 in which the plates extend on both sides of the rails for substantially the full lengths of the ties.

JAMES B. McWILLIAMS.
